UNITED STATES PATENT OFFICE

FRANK B. TOMLINSON, OF LOUISVILLE, KENTUCKY, ASSIGNOR TO REYNOLDS METALS COMPANY, OF LOUISVILLE, KENTUCKY

MEANS OF SEALING CARTONS

Application filed October 22, 1929. Serial No. 401,432.

The present invention relates to box forming devices and has particularly to do with a means for preparing foil covered blanks or material for assembly.

5 The invention consists generally in an improved means for slitting or "roughing" box or carton blanks or sheets.

In the accompanying drawings which form part of this specification and which illustrate 10 the preferred embodiment of the invention:

Figure 1 is a vertical detail, partly in section, of a feed device upon a well known box forming apparatus;

Figure 2 is a vertical sectional view on the 15 line 2—2 of Figure 1;

Figure 3 is a similar view on the line 3—3 of said Figure 1;

Figure 4 is a perspective view of the knife holder, partly in section;

20 Figure 5 is a fragmentary plan view taken on the line 5—5 of Figure 1;

Figure 6 is a specimen of a blank after it has been acted upon by the slitting device herein described and illustrated.

25 Reference should be had to the patents of E. G. Staude, numbered 1,104,013, folding and gluing machine, dated July 21, 1914, and numbered 1,033,040, feed device for flexible blanks or sheets, dated July 16, 1912, for illustrations of machines and the parts thereof 30 in connection with which the present invention is used.

In a conventional arrangement for feeding blanks to a box forming machine, such as 35 the Staude machine hereinabove referred to, there are arranged two parallel shafts 10 and 11, one above the other, for the pick-up drum and the pulleys. Keyed to the lower of these shafts are opposed heads 2, one only 40 of which is shown, and slidingly but firmly seated upon the heads 12 is a cylindrical drum 13 around which rubber belts or bands 14 travel.

Upon the upper shaft 11 and keyed thereto 45 are a plurality of pulleys 15, which are generally rubber faced. Pulleys 15 may be of any selected number and are suitably spaced one from another.

In juxtaposition to pulleys 15 and on shaft 50 11 is a second pulley 16 which is generally

metal faced and which is disposed to register with a blank slitting member hereinafter to be described. A side guide 17 for cartons going through the machine may be provided so that the adhesive receiving flap of a carton 55 will register with the said slitting device and the pulley 16.

For loading blanks preparatory to their insertion into the machine, generally one at a time, a feed table 18 is provided. This 60 table is mounted upon a bracket 19 suitably secured upon a bar 20 traversing the apparatus and along which the table may be moved. Said bar 20 may be secured in adjusted position by a lock nut 21 and key 22.

Upon the feed table 18 is a dished out seat 23 having thereon a rubber block 24. By means of a nut 25 on a screw 26, the screw 26 projecting through a forked extension of table 18, the position of said holder 18 and rubber block 24 relatively to the pick up members may be adjusted to compensate for changed thickness and other characteristics of the blank material. The screw 26 and nut 25, as well as a spring 26a, which is coiled 75 about screw 26 between the material of bracket 19 and the extension upon the table 18, to maintain the table 18 in any adjusted position, are not clearly shown, but these parts, spring 26a, screw 26, and nut 25 are 80 like similar members now to be described.

To the rear of holder 18 and resting thereupon is an auxiliary feeder board 27, generally adjustable, over which the carton blanks pass before entering the device. Between parts 27 and 18 a plate of metal, so marked, may be disposed.

Also disposed upon bracket 19 in the same manner as feed plate 18 is a knife holder 90 comprising a body 29, a blade holding section 30, and a bifurcated end 31. Suitably placed in the body 29 is an aperture 32 by which the holder is pivotally supported on said bracket 19.

In juxtaposition to holder 18, the knife holder 29 is always disposed, and said holder is held upon the bracket 19 in the same manner as table 18.

The bifurcated end 31 of the blade holder 29 has extending therethrough a screw 32.

secured in bracket 19, and about which is a coil spring 33 the force of which is urged upon the under side of bifurcated end 31. Thus the blade holder 29 is adjustably secured in position by the head or nut 34 upon screw 32, which is on the opposite side of end 31, said holder thus also being prevented from having a vibratory motion and is held against displacement from any adjusted position by the spring 33 which urges end 31 to maintain the position controlled by adjustment of nut 34.

In the blade receptacle 30, which is formed with a bottom plate 40 which is secured by screws upon member 29, is a plurality of blades 35. Between adjacent blades 35 are separators 36. Within the part 30 and beneath the blades 35 and separators 36 and above bottom plate 40 is a plate 37. This member is vertically adjustable by means of two or more machine screws 37a threaded in plate 40 and bearing upon the bottom of plate 37. By adjustment of plate 37, the penetration of the blades 35 into the flap of a carton blank is regulated.

The blades 35 are secured in any adjusted position by screws 38 threaded in one side of holder section 30. A stud 39 is disposed at the other side of said blade holder 30 and freely rotatable thereon is a roller bearing 41, the topmost portion of the periphery of which is above the horizontal cutting edge of blades 35.

As carton blanks go through the machine, the knives 35 are adapted to slit the flap, bearing 41 engaging a portion of the pulley 16 to insure accurate depth of slitting and to avoid a too deep penetration of the knives 35.

A bracket 42 is mounted upon a bar 43 traversing the machine somewhat above the shaft 11 and is secured thereon by a lock nut 44. A scraper having an angular body and a blade end 45 is mounted on said bracket so that the blade is adapted to scrape from pulley 16 particles of foil or paper which adhere thereto as a result of the destructive slitting of the carton flap.

Thus the foil covered surface of the carton blank is uniformly ruptured and roughened so that asphaltum or any other suitable adhesive may be applied to the flap of the carton blank to cause said flap to adhere to the blank in a proper position in the final assembly of the carton in the box or carton forming machine.

I claim:

1. A box forming machine comprising blank feeding means, a tray, knives in said tray, and a guide upon said tray cooperating with said feeding means to regulate the penetration of said knives into blanks.

2. A box forming machine comprising blank feeding means, a tray, knives in said tray, and a guide upon said tray cooperating

with said feeding means to regulate the penetration of said knives into blanks, and in which said feed means is of a rotary type, and said guide is a bearing engaging said feed means.

3. A box forming machine comprising roller blank feed means, a tray in juxtaposition thereto, knives in said tray, and means for locking said knives in said tray.

4. A box forming machine comprising roller blank feed means, a tray in juxtaposition thereto, knives in said tray, and means for adjusting the cutting edge of said knives relatively to said tray.

5. A box forming machine comprising roller blank feed means, a tray in juxtaposition thereto, knives in said tray, means for raising and lowering the knives in said tray, and means for securing said knives in any adjusted position.

6. A box forming machine comprising roller blank feed means, a tray in juxtaposition thereto, knives in said tray, and a roller bearing upon said tray engaging said feed means.

7. A box forming machine comprising roller blank feed means, a tray in juxtaposition thereto, knives in said tray, a guide bearing upon said tray defining its position with respect to said feed means, and means upon said tray for moving the knives therein toward said feed means independently of said tray guide bearing.

8. A tray for combination with a box folding machine, comprising a section for knives, knives in said section, means for raising and lowering the knives therein, and a guide for engaging said box folding machine.

9. A box forming machine comprising blank feeding means, a tray, penetrating means in said tray adapted to engage blanks in said feeding means, and a guide upon said tray cooperating with said feeding means to regulate the penetration of said penetrating means into blanks.

FRANK B. TOMLINSON.
